UNITED STATES PATENT OFFICE.

BENJAMIN KEYS, OF CHICAGO, ILLINOIS.

EGG-HOLDER.

SPECIFICATION forming part of Letters Patent No. 634,500, dated October 10, 1899.

Application filed January 11, 1899. Serial No. 701,795. (No model.)

To all whom it may concern:

Be it known that I, BENJAMIN KEYS, a citizen of the United States, residing at Chicago, in the county of Cook and State of Illinois, have invented certain new and useful Improvements in Egg-Holders, of which the following is a specification:

This invention relates to that class of devices which is used for the purpose of storing, holding, and shipping eggs, and has for its object the providing of a simple, economical, and efficient egg-holder.

A further object of the invention is to provide a simple, economical, and efficient egg-holder in which eggs may be placed and shipped from the producer to the consumer without being removed therefrom.

A further object of the invention is to provide a simple, economical, and efficient egg-holder which can be made from a paper-board or similar material and provided with dividing-partitions which act to hold the parts together and by which it may be lifted from place to place.

Further objects of the invention will appear from an examination of the drawings and the following description and claims.

The invention consists principally in the combination of an inclosing holder made from one piece of board or similar material and a dividing partition or partitions engaging therewith and which act to hold the parts together and by which it may be lifted from place to place.

The invention consists, further, in the combination of a holder composed of thin paper-board or similar material cut so as to provide end pieces, side pieces with end wings, and a dividing partition or partitions provided with projecting pieces arranged to be passed through the end pieces and wings to hold the parts together and by which the holder may be lifted from place to place.

The invention consists, further and finally, in the features, combinations, and details of construction hereinafter described and claimed.

In the accompanying drawings, Figure 1 is a plan view of the fiber or paper board which forms the inclosing or body portion of the holder laid out in a flat plane; Fig. 2, a plan view of the complete holder; Fig. 3, a side

elevation of the complete holder; Fig. 4, an end view of the complete holder; Fig. 5, a transverse sectional view taken on line 5 of Fig. 2; Fig. 6, a longitudinal sectional view taken on line 6 of Fig. 2; Fig. 7, a side elevation of one end of the longitudinal partition, and Fig. 8 an elevation of one of the transverse partitions.

60

In constructing an egg-holder in accordance with my improvements I make an inclosing or body portion from a flat piece of thin paper-board or similar material cut and punched so as to provide a bottom A, end pieces B and B', side portions C, provided with overlapping wing portions C', C², C³, and C⁴, all of which latter portions are provided with the shouldered perforations c, which when the parts are placed together, as shown in Figs. 70 2, 4, and 6, register with each other and through which projecting T-shaped heads of the longitudinal partition D are passed. This partition acts to lock the parts together and to afford means for lifting the tray or holder 75 from place to place.

In order to provide egg-holding compartments E, in which eggs may be placed, the longitudinal partition is provided with a number 80 of transverse partitions G are also provided, which are slotted at g in their upper parts, so that they may be interlocked with the longitudinal partition, as shown in Figs. 2 and 6, and then form the egg-spaces above noted. 85

To hold the parts more firmly in position, the transverse partitions are provided with small projecting lugs g' at their lower portions, arranged to be passed through slots or perforations a in the sides of the body portion, 90 as clearly shown in Figs. 3 and 5.

It is desirable that a cushion be formed in the bottom portion, upon which the egg may rest, so that in lifting the tray or holder from one place and depositing it in another the 95 shock will not break the eggs. In order to accomplish this result, the bottom portion has a plurality of cylindrical elevations, as at A', (shown clearly in Fig. 5,) so that when an egg is laid thereon the elevations form cushions to protect the eggs from being easily broken.

100 It is desirable that a space be provided between the ends of the tray or holder and the

case, in which it may be shipped or stored. In order to accomplish this result, the body portion is so punched or cut than when it is folded it provides projecting ends a' , which 5 form the necessary space between the tray or holder and the case in which it may be shipped and also acts to protect the projecting head portions of the longitudinal partition.

10 o While I have described my invention with more or less minuteness as regards details and arrangement and as being embodied in certain precise forms, I do not desire to be limited thereto unduly or any more than is 15 pointed out in the claims. On the contrary, I contemplate all proper changes in form and arrangement, the omission of immaterial elements, and the substitution of equivalents as circumstances may suggest or necessity 20 render expedient.

I claim—

25 1. In an apparatus of the class described, the combination of an inclosing holder composed of thin paper-board or similar material in one piece forming the bottom, sides and end portions and provided with perforations in its end portions, a longitudinal partition provided with headed extensions passed through the perforations in the end portions 30 to secure the parts together and to the sides and by which the holder may be lifted from place to place, and transverse partitions arranged in engagement with the longitudinal partition and said portions to form egg-spaces, substantially as described.

35 2. In an apparatus of the class described, the combination of an inclosing holder portion composed of thin paper-board or similar material forming the bottom, sides and end 40 portions cut to form end portions and overlapping wings on the sides and provided with perforations in the overlapping wings and end portions, transverse partitions having projecting lugs engaging with the side portions, and a longitudinal partition engaging 45 with the transverse partitions and provided with a T-shaped projection at each end passed through the end perforations of the overlapping wing portions of the holder for the purpose of securing the parts together and by 50 which the holder may be lifted from place to place, substantially as described.

55 3. In an apparatus of the class described, the combination of an inclosing holder formed of thin paper-board or similar material cut to form a bottom, sides with overlapping end

wings and end portions and provided with perforations in the overlapping wings and with projecting pieces a' at each end at or near the lower portion of the sides, transverse partitions having lugs passed through the side portions, a longitudinal partition provided with a T-shaped head at or near each end thereof passed through the perforations in the end pieces, and overlapping wings to 65 secure the parts together and enable the holder to be lifted from place to place at the longitudinal partition, substantially as described.

4. In an apparatus of the class described, 70 the combination of an inclosing holder formed of thin paper-board or similar material cut to form a bottom, sides with overlapping end wings and end portions and provided with perforations in the overlapping wings and with projecting pieces a' at each end at or 75 near the lower portion of the sides, transverse partitions having lugs passed through the side portions, a longitudinal partition provided with a T-shaped head at or near each end thereof passed through the perforations in the end pieces and overlapping wings to 80 secure the parts together and enable the holder to be lifted from place to place at the longitudinal partition, and elevated portions 85 in the bottom part to form a cushion in each of the egg-spaces upon which an egg may rest, substantially as described.

5. In an apparatus of the class described, 90 the combination of an inclosing holder formed of thin paper-board or similar material cut to form a bottom, sides with overlapping end wings and end portions and provided with perforations in the ends and overlapping wings and with projecting pieces a' at each 95 end at or near the lower portion of the sides, transverse partitions having lugs passed through the side portions, a longitudinal partition provided with a T-shaped head at or near each end thereof passed through the 100 perforations in the end pieces and overlapping wings to secure the parts together and enable the holder to be lifted from place to place at the longitudinal partition, and inverted-dish-shaped elevations in the bottom 105 portion, one in each of the egg-spaces, upon which an egg may rest, substantially as described.

BENJAMIN KEYS.
